FIG. 13

FIG. 1 is a top plan view of a nail clipper embodying my new design;

FIG. 2 is a side elevational view thereof;

FIG. 3 is a bottom plan view thereof;

FIG. 4 is a right end view thereof;

FIG. 5 is a left end view thereof;

FIG. 6 is a side elevational view thereof in operating position;

FIG. 7 is a top plan view of a portion thereof in operating position;

FIG. 8 is a top plan view of a modified form thereof;

FIG. 9 is a side elevational view of the modified form of FIG. 8;

FIG. 10 is a bottom plan view of the modified form of FIG. 8;

FIG. 11 is a right end view of the modified form of FIG. 8;

FIG. 12 is a left end view of the modified form of FIG. 8;

FIG. 13 is a side elevational view of the modified form of FIG. 8 in operating position;

FIG. 14 is a top plan view of a portion of the modified form of FIG. 8 in operating position.

The dominant features of my new design are shown in solid lines in the drawings, and the common features of the two illustrated embodiments of my new design consist primarily of a generally oval built-up finger gripping surface formed adjacent the distal end of each of the relatively movable elements of the clipper, the major axis of each oval being aligned with the longitudinal axis of the clipper.

I claim:

The ornamental design for a nail clipper, as shown and described.
